PNEUMATIC DRILL CONSTRUCTION

William Brooks DeGroff, Bryan, Ohio, assignor to Aro Equipment Corporation, Bryan, Ohio, a corporation of Ohio

Application February 7, 1955, Serial No. 486,495

3 Claims. (Cl. 77—33.5)

The present invention relates to a portable automatic drill of the pneumatically operated type.

It is a primary object of this invention to provide an improved drill construction, wherein pneumatic means serve to effect power drive of the drilling tool, and to effect both forward and reverse reciprocation thereof.

It is another object to provide an air motor driven and air reciprocated drill construction, wherein oil dash-pot and by-pass valve means serve to adjustably regulate the speed of forward drilling movement.

It is a further object to provide oil dash-pot means for a pneumatically operated drill, wherein by-pass port means operatively responsive to the forward position of the drilling tool and variably adjustable closure means limiting the operability of said port means serve to permit initial rapid traverse of said drilling tool for a predetermined distance followed by slow forward movement thereafter, whereby the work may be approached quickly and the actual drilling performed more slowly.

It is still another object to provide auxiliary oil reservoir and valve means serving to automatically replenish the main oil supply of the dash-pot means of an automatic drill, thereby obviating the need for frequent oil replenishment during normal drill operation.

It is still a further object to provide an automatic drill of the air operated type which is readily adaptable to different stroke length, thereby eliminating the necessity for a range of tools to perform a variety of working operations.

It is yet another object to provide an automatic drill of the air operated type having a removably detachable arrangement of parts providing interchangeable gearing assemblies to permit a variety of different drill speeds with a single drill by simple interchange of gearing units.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which:

Figure 1 is a side elevational view, partly broken away and in section, showing a portable automatic drill of the air-operated type embodying the features of the present invention;

Figure 2 is a transverse cross-sectional view taken substantially as indicated by the line 2—2 on Figure 1;

Figures 3 and 3A together constitute a longitudinal cross-sectional view of the portable automatic drill of Figures 1 and 2, wherein Figure 3 illustrates the rear portion of the drill and Figure 3A is a continuation thereof illustrating the forward portion of the drill;

Figure 4 is a transverse cross-sectional view taken substantially as indicated by the line 4—4 on Figure 3A.

Figure 5 is a fragmentary view of a portion of combined Figures 3 and 3A, illustrating the operation of the adjustable rapid traverse means.

Referring now more particularly to Figure 1 of the drawing, I have shown a portable pneumatic drill 10 comprising

2

the major structural components of an oil chamber and air motor section 12, an air piston section 14, a control valve section 16, a nose housing 18, and a rear sleeve guard 20.

The oil chamber and air motor section 12 comprises an oil chamber housing 22 and an air motor housing 24, as best seen in Figures 3 and 3A. The housings 22 and 24 are co-axially and concentrically aligned in spaced relation to define therebetween the main chamber 26 of an oil dash-pot means.

10 The air motor housing 24 encloses an air motor assembly indicated generally at 28. The air motor 28 is of the well-known type comprising a plurality of vanes 30 carried by a drive shaft 32 mounted for rotation about a longitudinal axis by means of suitable bearing assemblies 34 and 36. 15 The forward end of the drive shaft 32 is splined at 33 for operative connection in readily detachable manner to a gearing assembly indicated at 38.

An oil retaining sleeve 40 is disposed outwardly of the air motor housing 24 in surrounding relation thereto, 20 and is screw-threadedly carried by the inner wall portions of the oil chamber housing 22. Suitable O-ring seals 44 and 46 provide a fixed oil-tight seal and a slidable oil-tight seal, respectively.

An oil screw 48 is screw-threadedly received within a 25 tapped hole providing an oil vent port 50 which extends through the oil chamber housing 22 for communication between the oil chamber 26 and the exterior. A suitable O-ring seal 52 is provided for oil-tight closure of the port 50 by the screw 48.

30 The forward end of the oil retaining sleeve 40 is screw-threaded at 56 to mountingly receive the nose housing 18 thereon. A wiping seal 58 is provided inwardly of the sleeve 40 for sliding cooperation with the reciprocably movable air motor housing 24, as will hereinafter become 35 apparent.

The splined forward end 33 of the motor drive shaft fixedly carries a drive gear 60 (see Figures 3A and 4), which meshes with a surrounding pair of planet gears 62 and 64. The gears 62 and 64 are rotatably supported by 40 means of suitable needle bearings 66 on a pair of drive pins 68 and 70, respectively. The drive pins 68 and 70 are received within a drive fitting 72 which is rotatably supported by means of bearings 74 within a fixedly positioned sleeve member 76. The sleeve 76 provides stationary gear teeth internally thereof which mesh with the planet gears 62 and 64. An end cap 80 is screw-threaded onto the sleeve member 76 to retain the various parts of the gearing unit in assembled relation. In this manner, driving rotation of the air motor drive shaft 32 is transmitted to provide driving rotation of the fitting 72 at a predetermined speed.

45 The forward terminal end of the drive fitting 72 receives thereon a slinger ring 82 which abuts against a thrust ring 84, and is screw-threaded for fixedly carrying a drill chuck assembly 86 thereon. A suitable drilling tool carried by the chuck assembly 86 may thereby be driven by the air motor 28.

The rear end of the air motor housing 24 is enlarged in a radially outward manner to provide a dash-pot piston 90 which slidably engages the internal surface of the oil chamber housing 22, and abuts in its rearmost position against an internal shoulder portion 23 of the housing 22. An O-ring seal 92 maintains oil-tight contact between the dash-pot piston 90 and the housing 22, thereby defining the length of the main oil chamber 26 between the oil retaining sleeve 40 and the dash-pot piston 90. 55 Rearward of the piston 90, the air motor housing 24 terminates in an end collar 94, which is externally screw-threaded. Inwardly thereof, the housing 24 provides a central bore terminating in a screw-threaded recess 96.

60 The air piston section 14 of the drill extends rearwardly of the oil chamber and air motor section 12, and in

cludes an air piston inner sleeve 100 which is screw-threaded onto the end collar 94 of the air motor housing 24. A hollow air feed tube 102 is screw-threadedly received within the recess 96, and provides a flow conduit for supplying compressed air from a suitable source of supply, as regulated by valve control means, to the air motor 28. A pair of O-ring seals 104 are provided between the inner sleeve 100 and the oil chamber housing 22. An air bleed-off passage 106 communicates from the interface between sleeve 100 and housing 22 to the exterior, thereby permitting trapped air to be bled-off. An O-ring seal 108 is also provided at the interface between the air feed tube 102 and the air motor housing 24.

The rearward end of the air piston section 14 is rigidly coupled to the control valve section 16 which provides a valve head assembly 120. An air piston 122 is slidably carried on the air feed tube 102, and provides an acting face 124 for forward drill feed and an acting face 126 for reverse drill movement. A forwardly extending collar portion 128 of the air piston 122 is externally screw-threaded to receive the rear end of the air piston inner sleeve 100. Suitable O-ring seals 130 and 132 are provided for oil-tight engagement at the interfaces between the air piston collar 128 and the air feed tube 102 and inner sleeve 100.

An air piston outer sleeve 134 is screw-threadedly attached at its forward end to the oil chamber housing 22 and at its rearward end to the valve head assembly 120. An O-ring seal 135 is provided at the interface between the relatively movable air piston 122 and the outer sleeve 134 to provide an air-tight seal between a reversing air space 136 and a forward feeding air space 138.

Suitable valve means having both manual and automatic control actuators are provided within the valve head assembly 120 substantially in accordance with the teachings set forth in my co-pending application, Serial No. 476,317, filed December 20, 1954. The details of the air motor valve means and actuators do not form a part of the present invention and have not been described in detail herein, reference being invited to the aforesaid co-pending application for details of construction.

During operation, the valve head assembly 120 will serve to provide air pressure at the forward acting surface 124 of the air piston 122 to effect forward sliding movement of the air piston 122 and the parts 24, 100 and 102 carried thereby. At the same time, air will be supplied through the hollow air feed tube 102 to the air motor 28 to effect driving rotation thereof. For reverse movement of the drilling tool, the valve head assembly 120 will serve to provide air pressure at the reverse acting face 126 of the air piston 122, thereby moving the air piston rearwardly, as well as the various parts carried thereby including the air motor.

An oil piston 140 is slidably carried on the air feed tube 102, and effects oil-tight engagement at the interfaces with the air feed tube 102 and the air piston inner sleeve 100, O-ring seals 142 and 144 being provided therefor. A loading spring 146 is biased in compression between the oil piston 140 and the collar portion 128 of the air piston 122. The spring 146 serves to maintain a force against the oil piston 140 tending to move its forwardly along the air feed tube 102. An oil screw 148 effects an oil-tight closure of a tapped hole forming a passageway 149 extending through the oil piston 140.

An auxiliary oil reservoir or chamber 150 is defined forwardly of the oil piston 140, and is normally filled to capacity with oil. A flow conduit 152 provides communication from the auxiliary oil chamber 150 through the air motor housing 24 to the main chamber 26. A spring-loaded ball valve 154 is interposed in the conduit 152. The normal closing bias of the valve 154 is sufficiently small so that a pressure differential between the chambers 26 and 150, resulting from a lowered pressure in the chamber 26 due to loss of oil therefrom, will effect an opening of the valve 154 and a consequent flow of oil

from the chamber 150 to chamber 26 by the loading force of the oil piston 140, thereby replenishing the main chamber oil loss.

A passageway 158 is provided through the dash-pot piston 90, and a one-way slide valve 160 is disposed therein. The valve 160 is arranged so that pressure thereagainst during forward movement of the piston 90 through the main chamber 26 will effect closure of the passageway 158, while rearward movement will effect valve opening to permit free flow therethrough.

As best seen in Figure 2 of the drawing, an adjustable by-pass valve 166 is provided to permit oil flow from one side of the dash-pot piston 90 to the other during reciprocation thereof within the main chamber 26. The by-pass valve 166 is screw-threadedly received within a transverse bore 168 formed in the oil chamber housing 22. The valve 166 is of reduced diameter at 170 for receiving a key pin 172 to effect locking of the valve 166 against removal from the bore 168 while permitting lengthwise adjustment. A lock washer 174 is also provided for securely fixing the by-pass valve 166 in position.

The valve 166 is formed with a reduced diameter forward end 176. An O-ring seal 178 engages the bore 168 to provide an oil-tight seal while permitting lengthwise movement of the valve 166 therein. A valve oil chamber 180 is defined between the forward end of the valve 166 and the walls of the bore 168.

The valve chamber 180 communicates with a passageway 182 (see Figure 3) leading to a forward acting face 184 of the dash-pot piston 90. The valve chamber 180 also communicates with a passageway 186 (see Figure 2) which extends in a transversely outward direction to an elongated axial passageway 188 (see Figures 2, 3, and 3A). The axial passageway 188 communicates at its forward end with a transversely inwardly directed passageway 190 (see Figure 3A) which leads to the chamber 26 for flow communication with a reverse acting surface 192 of the piston 90. It will be apparent that the passageways 190, 188, 186 provide communication with the valve chamber 180 at the reverse side of the piston 90, and the passageway 182 provides communication with the valve chamber 180 at the forward side of the piston 90.

The by-pass valve 166 terminates at its inner end in a tapered closure pin 194, which cooperates with the passageway 186 at its point of communication with the valve chamber 180 to determine the size of the annular orifice formed therebetween. In this way, the rate of flow from one side of the dash-pot piston 90 to the other side may be adjustably varied by rotating the valve 166 so as to screw it forwardly or rearwardly of its length to vary the orifice size. It will be clearly apparent that by providing a relatively large orifice size the resistance pressure load in the dash-pot main chamber 26 will be reduced so as to permit the piston 90 to be more readily reciprocated therethrough, resulting in more rapid forward drill feeding movement. Conversely, close restriction of the orifice size by the tapered pin 194 will result in increased resistance to by-passing flow around the piston 90 during forward movement thereof, and a consequent slower rate of forward movement of the drill. In this way, the speed of drill feed may be readily and simply predetermined by the operator.

The main oil chamber 26 and the auxiliary oil reservoir 150 are initially filled with hydraulic fluid in the following manner. The drill 10 is held in a generally horizontal position and the air piston is run forward a short distance so as to free the air piston face 124 and the dash-pot piston face 184 to permit the various inner drill parts to turn freely.

The rear sleeve guard 20 and the nose housing 18 are first removed. The valve head assembly 120 is then unscrewed from the air piston section 14 and removed. The air piston outer sleeve 134 may then be unscrewed from the oil chamber housing 22 and removed. The air pis-

ton 122 is now fully exposed and may be unscrewed from the air piston inner sleeve 100 and slid off the rear end of the hollow air feed tube 102. The spring 146 is also removed.

The oil level in the main oil chamber 26 should next be checked. The drill 10 is held in a vertical position with its forward or tool end upward, and the following steps taken. The oil screw 48 and O-ring seal 52 are removed from the port 50 of the oil chamber housing 22. The oil retaining sleeve assembly 40 is then unscrewed and removed from the housing 22. The oil level in the main oil chamber 26 should be level with the port 50. If the oil level is below this point, it is necessary to replenish the supply of oil to raise the level to the desired point. The oil retaining sleeve assembly 40 may then be replaced. Excess oil and entrapped air will bleed outwardly through the port 50 as the sleeve assembly 40 is screwed into the housing 22. The oil screw 48 and O-ring 52 may then be replaced.

The position of the drill 10 is then reversed and held in a vertical position with the nose or tool end of the drill pointed downwardly. The oil screw 148 and its O-ring are removed from the passageway 149 of the oil piston 140. Suitable means may then be inserted into the tapped hole 149 to enable the oil piston 140 to be slid upwardly and off of the air feed tube 102. The bore between the air feed tube 102 and the air piston inner sleeve 100 is then fully exposed to permit access to the auxiliary reservoir 150. A predetermined quantity of hydraulic oil may then be poured in to fill the auxiliary oil chamber 150 with the necessary quantity of fluid. In the particular drill construction which I have illustrated, about 3 ounces of hydraulic fluid are required.

The oil piston 140 may then be replaced. The oil piston 140 is slid downwardly along the air feed tube 102 until the oil within the reservoir 150 begins to bleed upwardly through the tapped hole 149. In this way, entrapped air within the oil reservoir 150 is eliminated. The oil screw 148 may then be replaced. The spring 146 is then returned to its proper position, and the air piston 122 slid onto the air feed tube 102 and screwed into the air piston inner sleeve 100. The air piston outer sleeve 134 and the valve head assembly 120 are then replaced. The sleeve guard 20 and nose housing 18 may then be returned to position, thereby completing reassembly of the drill 10.

The main oil chamber 26 will now be completely filled with oil. The auxiliary oil reservoir will also be completely filled with oil and subjected to a loading pressure by the spring biased oil piston 140. As normal leakage occurs from the main oil chamber 26 during operation of the drill, the spring loaded ball valve 154 will be unseated in response to demand to permit a replenishing supply of oil to be introduced to the main chamber 26 from the auxiliary oil reservoir 150. In this way, a substantial quantity of replenishing oil will be continuously and automatically available for maintaining the main oil chamber 26 filled at all times. The drill 10 may be subjected to continuous operation over substantially long periods of time, without any necessity for withdrawing the drill from use and disassembling it for oil replenishment. Whereas drills of this type now employed must be serviced at frequent intervals, usually weekly, the provision of an auxiliary oil supply in the manner disclosed herein permits continuous drill operation for periods of time in excess of one month without any necessity for oil replenishment.

I have also provided rapid traverse adjusting means to permit the drilling tool to be initially moved forwardly toward the work at a relatively high rate of speed, and thereafter fed forwardly during the drilling operation at a substantially lower rate of speed as predetermined by the adjustment of the by-pass valve 166. For this purpose I provide a by-pass passageway 200 formed in the oil chamber housing 22 (see Figure 3). The pas-

sageway 200 terminates at its rear end in a cross port 202 closely adjacent the interface between the piston 90 and an abutment surface 23 of the oil chamber housing 22. A plurality of rapid traverse adjustment ports 204 are provided between the dash-pot chamber 26 and the by-pass passageway 200 forwardly of the piston 90 when in its rear position of engagement against the housing abutment shoulder 23.

10 A slideable pin 206 is received within the by-pass passageway 200 and is of sufficient length to effect closure of all the ports 204, as shown in Figure 3. It will be apparent that with all the ports 204 obstructed by the slideable pin 206, the speed of movement of the dash-pot piston 90 through the chamber 26 will be determined

15 solely by the adjustment of the by-pass valve 166. A knob 208 is screw-threadedly received within an enlarged head end 210 of the slideable pin 206. The knob 208 may be tightened to effect a locking of the head 210 in position, thereby fixedly determining the relation of the pin 206 to the ports 204. A guide slot 212 extends forwardly within the oil chamber housing 22 to permit the pin 206 to be adjustably positioned for exposing one or all of the ports 204. In this way, by-pass flow through the ports 204, passageway 200 and port 202 may be provided to permit rapid forward traverse of the piston 90.

20 In Figure 5 of the drawing, I have shown a position of adjustment wherein several of the ports 204 have been exposed. It will be apparent that as the piston 90 moves forwardly from its rearmost position, oil within the main chamber 26 will be rapidly by-passed, and the rate of forward movement will be relatively rapid. When the piston 90 has reached a forward position overlying all of the exposed ports 204, by-pass flow therethrough will be discontinued, and the by-pass adjustment of the valve 35 166 will then determine the speed of forward feeding movement. It is possible, therefore, to permit the drill to move rapidly forward to the work, and then to continue movement at a substantially slower rate of speed for actual drilling operation. Such rapid traverse adjustment permits a substantial saving of operator time by minimizing the usual waiting time for running the drilling tool forwardly up to the work.

30 As seen in Figure 1, a plate 214 is externally mounted on the drill adjacent the knob 208, and is provided with 45 suitably calibrated indicia for indicating the predetermined distance of initial rapid traverse movement.

It will be understood that when forward drilling movement is terminated, and the drill is reversed for withdrawal or return movement, the one-way valve 160 is 50 opened by the pressure force of the oil within the dash-pot chamber 26 to permit flow directly through the piston 90, thereby resulting in relatively rapid drill movement in the reverse direction. A practical mounting of the drill 10 for working operation is shown in Figure 1. An 55 adaptor cap 220 is screw-threadedly received within the nose housing 18 and serves to carry a flanged connector member 222 which cooperates with a bayonet slot formed in a complementary mounting member 224 which is fixedly secured to a piece of work 226. A drill bit or tool 228 is carried by the drill chuck, and may be fed forwardly and thereafter withdrawn to provide a drilled hole 230 in the work 226.

60 It will be apparent that the conventional use of various fittings and mounting elements for fixedly positioning the drill relative to the work results in a substantial distance between the end of the drill tool 228 and the surface of the work 226. If this distance is, say, 2 1/8 inches, the knob 208 of the traverse adjusting means will be slid forwardly by the operator and locked in position at the marking on plate 214 designated "2 1/8." This adjustment will serve to expose a predetermined number of by-pass ports 204, resulting in oil by-pass to permit the dash-pot piston 90 to move forward rapidly through the main chamber 26 for an initial distance of nearly 2 1/8 inches. At this point, the previously exposed ports 75 204

will be fully closed by the piston 90, and further forward movement of the drilling tool will then be governed by the predetermined rate of drilling speed controlled by the by-pass valve 166. Upon reversal of drill movement, the dash-pot piston 90 will return through the main chamber 26, and the valve 160 will open to permit oil flow through the piston for rapid return movement.

As best seen in Figure 3A of the drawing, it will be apparent that the entire gearing assembly 38 may be readily removed from the motor drive shaft 32 as a single integral unit. I contemplate by the present invention the provision of various other gearing assemblies providing a variety of motor speeds for interchangeable mounting on the air motor shaft 32. Both single reduction and double reduction gearing units may be employed. For large ratio reduction units, the gearing assemblies may be of substantially greater length than that illustrated. In such cases, it may be necessary to replace the nose housing 18 with an alternative nose housing to accommodate the different gearing assembly size and position of the drill chuck assembly.

By using various gearing assemblies, which may be readily interchanged, it is possible to employ the same single drill unit for a wide variety of working operations. For example, I may provide gearing assemblies permitting available drilling speeds of 350, 650, 1200, 2500, and 4600 R. P. M. with the same drill unit.

In order to effect change from one gearing assembly to another it is merely necessary to remove the nose housing 18, drill chuck assembly 36 and slinger ring 82. The entire gearing assembly 38 may then be axially slid forwardly off the splined end 33 of the motor drive shaft 32. The gearing assembly of required speed may then be replaced on the motor shaft, and the slinger ring, drill chuck, and nose housing returned to their former positions.

Changes may be made in the construction and arrangement of the parts of my pneumatic drill construction without departing from the real spirit and purpose of my invention, and it is my intention to cover by the claims any modified forms of structure or use of mechanical improvements which may be reasonably included within their scope.

What I claim as new and desire to obtain by Letters Patent of the United States is:

1. A pneumatic drill comprising a casing forming a pair of elongated chambers arranged in longitudinally spaced relation, longitudinally aligned air piston means reciprocably mounted for forward and reverse movement within said casing, the forward end of said air piston means carrying within the forward chamber an air motor adapted to effect driving rotation of a tool, the rear end of said piston means carrying within the rear chamber a double-acting piston adapted to effect reciprocation of said air piston when actuated, hydraulic piston means carried by said air piston means within said forward chamber and cooperating with hydraulic fluid contained therein to provide dash-pot means for regulating the speed of reciprocation of said air motor, valve means carried by said dash-pot piston and operative to regulate forward and reverse flow of hydraulic fluid therethrough to effect relatively slow forward movement and relatively rapid reverse movement of said air motor when reciprocated, and an auxiliary fluid reservoir disposed within said air piston means and having passage means communicating with said forward chamber, said passage including valve means and said reservoir being pressure loaded for cooperation with said valve means to automati-

ically effect replenishment of hydraulic fluid losses from said one chamber during drill operation.

2. A pneumatic drill comprising a casing forming a pair of elongated chambers arranged in longitudinally spaced relation; an air motor reciprocably mounted for forward and reverse movement within one of said chambers and adapted to effect driving rotation of a tool, double-acting piston means disposed within said other chamber and operatively connected to said air motor to effect reciprocation thereof when actuated, piston means carried by said air motor within said one chamber and cooperating with hydraulic fluid contained therein to provide dash-pot means for regulating the speed of reciprocation of said air motor, supplemental regulating means operative in response to the forward position of said air motor to effect control of said dash-pot means for providing rapid traverse of said air motor through a predetermined initial distance, said supplemental regulating means comprising longitudinally elongated port means formed within said casing forwardly of said dash-pot piston when in its rearmost position, said port means providing flow communication through by-pass conduit means from the forward to the reverse side of said dash-pot piston, and longitudinally elongated closure means axially slidable along said casing for fully closing said port means and for opening said port means progressively forwardly to permit selective predetermining of the extent of initial rapid traverse, thereby adapting said drill to provide a range of operating strokes.

3. A pneumatic drill comprising a casing forming a pair of elongated chambers arranged in longitudinally spaced relation, an air motor reciprocably mounted for forward and reverse movement within one of said chambers and adapted to effect driving rotation of a tool, double-acting piston means disposed within said other chamber and operatively connected to said air motor to effect reciprocation thereof when actuated, piston means carried by said air motor within said one chamber and cooperating with hydraulic fluid contained therein to provide dash-pot means for regulating the speed of reciprocation of said air motor, supplemental regulating means operative in response to the forward position of said air motor to effect control of said dash-pot means for providing rapid traverse of said air motor through a predetermined initial distance, said supplemental regulating means comprising an axially aligned plurality of longitudinally spaced ports formed within said casing forwardly of said dash-pot piston when in its rearmost position, each of said ports providing flow communication through by-pass conduit means from the forward to the reverse side of said dash-pot piston, longitudinally elongated closure means axially slidable along said casing for fully closing said ports and for opening said ports successively forwardly to permit selective predetermining of the extent of initial rapid traverse, thereby adapting said drill to provide a range of operating strokes, and variably adjustable orifice means in said by-pass conduit means for regulating the rate of by-pass flow therethrough to permit control of initial rapid traverse speed.
